CLAIM

The ornamental design for a security sensor as shown and described.

DESCRIPTION

FIG. 1 is a front bottom perspective view of a security sensor showing our new design;

FIG. 2 is a rear top perspective view thereof;

FIG. 3 is a front elevational view thereof;

FIG. 4 is a rear elevational view thereof;

FIG. 5 is a right-side view thereof;

FIG. 6 is a left-side view thereof;

FIG. 7 is a top plan view thereof; and

FIG. 8 is a bottom plan view thereof.

The broken line showing is included for the purpose of illustrating portions of the "article" and forms no part of the claimed design.

1 Claim, 4 Drawing Sheets
